UNITED STATES PATENT OFFICE.

EDWARD F. DAVIS, OF LYNN, MASSACHUSETTS, ASSIGNOR OF ONE-FOURTH
TO WARREN H. CALDER, OF LYNN, MASSACHUSETTS.

SHEARS OR SCISSORS GRINDING APPARATUS.

No. 811,202.

Specification of Letters Patent.

Patented Jan. 30, 1906.

Application filed September 26, 1904. Serial No. 225,895.

To all whom it may concern:

Be it known that I, EDWARD F. DAVIS, a citizen of the United States, residing at Lynn, county of Essex, State of Massachusetts, have invented an Improvement in Shears or Scissors Grinding Apparatus, of which the following description, in connection with the accompanying drawings, is a specification, like characters on the drawings representing like parts:

This invention has for its object the production of a novel apparatus for grinding shears, scissors, and the like.

The machine comprises an emery-wheel, which is rotated, and a clamp for holding the shear-blade, the clamp being moved longitudinally that the edge of the blade may be acted on from one to its other end.

I have shown the apparatus as provided with a locking device that prevents the rotation of the emery-wheel until, for instance, the locking device is unlocked by the insertion of a coin, for the apparatus may be started and turned for a sufficient length of time to grind shears or scissors, when the apparatus will be again locked, but can be started again by the insertion of a coin.

Figure 1 in rear elevation shows a grinding apparatus embodying my invention in one of the best forms now known to me. Fig. 2 is a detail to the left of the dotted line z , Fig. 1. Fig. 3 is a detail showing the bell and apparatus for moving the hammer for striking the bell at the desired time. Figs. 4, 5, and 6 represent specific details of the locking feature, to be hereinafter referred to. Fig. 7 is a left-hand end view of the machine shown in Fig. 1. Fig. 8 is a section through the screw and guide-rod, showing the carriage sustaining the shear-carrier, which in practice is provided with a clamp. Figs. 9 and 10 are details of the clamp.

The framework of the apparatus herein to be described comprises a base A, adapted to be connected to a bench or other platform A' by suitable screws A². The base has rising therefrom suitable uprights A³, that sustain the working parts of the machine. The main shaft B of the machine is provided, as shown, with a belt-pulley B', having a handle B², by which to rotate the same, said pulley driving a belt B³, that is extended over a smaller belt-pulley B⁴, connected with a shaft B⁵, mounted in suitable bearings of

arms A⁶ and provided at its opposite end with a large driving-wheel B⁶, over which is extended a driving-belt B⁷, that in turn contacts with the grooved hub B⁸, connected with the shaft B⁹, which shaft carries the emery or other suitable grinding wheel B¹⁰, which is rotated at speed to effect the grinding of the edges of the shears or scissors. The shaft B has a toothed gear C, that engages and rotates in unison with it a toothed gear C', fast on a stud C², sustained in the framework, the two gears C and C' being rotated in opposite directions. Either of these gears is made a driver for a pinion C³, secured to the end of a screw C⁴, sustained in a swinging frame or yoke C⁵, mounted to turn about a center C⁶.

A spring C⁷ (see Fig. 7) acts normally to keep the pinion C³ in mesh with the gear C and turn the screw-shaft in a direction to cause the movement of the shears to be described in a direction to cause the stone to act from near the pivotal point of the shears to the point thereof.

The shears having been ground along the edge, as described, it is frequently desirable to reverse the movement of the shears, that the grinding-wheel may act longer upon the edge, and to effect this the user of the apparatus will operate a rod a, that in turn is jointed to an arm a', extended from the rocking frame referred to, so that said frame and its screw-shaft and pinion may be turned from the position shown in Fig. 7 to the left, that the pinion C³ may be engaged by the gear C' and the direction of rotation of the screw be reversed.

The screw is embraced by the lower ends or hubs b of a two-part carriage b' b², said hubs being tapped to receive the screw and be slid longitudinally by the rotation of the screw. The upper end of the part b' of the carriage has a stud b³, that enters a slot b⁴ in the depending arm of the part b² of the carriage, (see Fig. 8,) the upper end of the part b² being bored to receive a short tube b⁵, (see Fig. 1,) that embraces and slides freely on the guide-rod b⁶, sustained in a yoke b⁷, having ears and connected with the framework by a bolt b⁸. The short tube b⁵ is embraced by the foot of an arm c, provided at its lower end, as shown, with an eye c', with which is engaged a spring c², the lower end of the spring being connected, as may be desired, with one

or the other of the series of hooks c^3 c^4 c^5 , according to the weight of the shears or scissors being ground.

The arm c has a hole 2 at its upper end, (see Fig. 8,) that receives a stud-screw 3, Fig. 1, the latter receiving loosely over it an ear 4 of a clamp-holder d , said clamp-holder receiving loosely through that part thereof at right angles to the ear 4 a right-angled stud extended therethrough loosely from the rear side of the main member e of the shears or scissors clamp, the other member being a thumb-screw e' , the threaded part of which enters a hole tapped in the main member e in line with the longitudinal axis of the stud. The free end (see Figs. 7 and 10) of this stud is threaded to receive a nut d^2 , a spring d^3 being interposed between the nut and the clamp-holder to aid in holding the clamp in any position in which it may be placed by the person using the apparatus.

To insert a pair of shears into the machine to be ground, the thumb-screw will be loosened and the back of the shear-blade will be inserted between the thumb-screw and the face of the main part of the clamp, the back of the shears or scissors meeting suitable stops 6, (see Fig. 9,) and thereafter the thumb-screw will be set up, clamping the shears or scissors blade and holding the same firmly while the emery-wheel is being rotated to grind the same. The handle f of the shear or scissor blade being ground will be engaged by one hand of the person, for instance, who is looking after the grinding, and it may be the same person who is turning the wheel B' . The arm c may be turned up or down on the tube surrounding the guide-rod b^6 , and the edge of the shears or scissors may be held with greater or less force, as may be desired, against the grinding-wheel. I have shielded the rear part of the grinding-wheel by a hood g .

Thus far I have described the grinding-wheel and the means for moving it, and I will now describe the mechanism for locking the apparatus to restrain its use except by authorized persons.

It is contemplated placing the machine herein described in barber-shops and other places where scissors will be ground, and to insure that the apparatus bring in an income means have been provided to lock the apparatus, so that it could not be rotated except, for instance, by the placing of a coin in the apparatus. To provide for this, the framework sustains at its rear side a casing comprising disks h h' , which in practice will be embraced by a suitable covering, so that the apparatus sustained by the disks and inclosed within the covering may be shielded from being tampered with. In the drawings I have omitted the shields or covering, showing only the holes in the disks, to which the shields may be attached. The left - hand shield sustains a stud h^2 , (see Fig. 2,) on

which is mounted loosely a ratchet-toothed wheel h^3 , having a lateral tooth h^4 . The ratchet-wheel h^3 is rotated intermittently or step by step by projections 8, connected with a collar 9, secured to the main shaft B by means of a set-screw 10. The disk h' has a projection h^5 at its inner side, and within said projection the disk sustains a stud-screw h^6 , on which is mounted loosely a ratchet-toothed wheel h^7 , having a connected plate h^7x , provided with a cam-ledge h^8 and with a locking projection h^9 . The toothed wheel h^7 is engaged by the tooth h^4 and moved one step at every revolution of the ratchet-toothed gear h^3 . The disk h has extended above it a chute m' , comprising two plates held together by suitable screws m^2 , there being between said plates a throat (shown best by dotted lines, Fig. 3) into the mouth 10 of which is inserted a coin, which may be a nickel. The lever or arm m^4 is slotted vertically to constitute a pocket, in which enters the coin dropped into the chute, the lower edge of said coin meeting the inturned end n (see Fig. 4 and 5) of a coin-rest, shown as an arm of wire, standing vertically in a hole in said lever or arm and having at its upper end another arm with which is connected a spring n' , the latter normally keeping the lower bent end of the rest across the pocket referred to, so that the coin is retained therein until the rest is moved, as will be described, to withdraw its lower bent end from underneath the coin. The lever or arm m^4 is mounted on a pivot m^9 , sustained in an ear m^{10} , extended from the disk 8. The opposite end of the lever m^4 has a yielding finger m^6 , (see Fig. 5,) that enters a loop m^7 , connected with the rear side of a locking-arm m^8 , the acting end of which is normally overbalanced to stand in the path of movement of the locking projection h^9 referred to, and when said locking-lever occupies the position shown in the drawings the driving mechanism is locked. The locking-lever m^8 is also mounted loosely on the opposite end of the stud m^9 , and said lever has extended therefrom an arm m^{12} , on which is adjustably mounted a weight, being normally located so as to let the end m^8 remain down, the weight, however, being adjustable to accommodate the weight of the coin used.

Assuming that a coin is dropped into the chute, it leaves the chute and enters the pocket in lever m^4 , turns the same so that the yielding arm m^6 , the end of which is in contact with the loop m^7 , lifts the heavier end of the slightly-overbalanced locking-lever m^8 from the position shown in the drawings sufficiently to let the locking projection h^9 pass the end of said lever, which it will do when the apparatus is started by turning the wheel B' after dropping a coin into the chute.

The cam represented by h^8 is supposed to be rotated in the direction of the arrow there on, Figs. 2 and 3, and gradually the low part

of said cam meets a shoe 20 at one end of an arm 21 on the hammer-lever 22, pivoted at 23, said shoe being normally kept pressed toward said cam-ledge by a spring 24, the free 5 end of which engages a notched projection 25 of said lever. The hammer-lever when the heel or high part of the cam-ledge m^s passes the shoe is turned normally by the spring 24, so that the upper end of said lever meets and 10 strikes a gong-bell p of usual construction. Just before the shoe leaves the heel of the cam-ledge the hammer-lever meets the upper arm 14 of the coin-rest (see Fig. 3) and turns the same against the stress of the spring n' , 15 removing the lower end of the rest from its position crossing the pocket of the lever m^s , letting the coin drop. The speed of movement of the cam-ledge is such that by the time the hammer-lever meets the shoulder 20 the grinding-wheel has been moved for a sufficient length of time to grind one of the blades of the shears.

As herein provided for, a nickel will be required for grinding each blade of the shears 25 or scissors.

Having described my invention, what I claim as new, and desire to secure by Letters Patent, is—

1. In a machine of the class described, a 30 grinding-wheel, a carriage having a shear-clamp mounted thereon, means for swinging the carriage toward and from the grinding-wheel, a screw-shaft engaging one end of said carriage, means for turning the screw-shaft 35 in one direction, means for turning the screw-shaft in the opposite direction, and a swinging frame carrying said screw-shaft, whereby it may be swung into operative relation with either of said means.

2. In a machine of the class described, a carriage, shear-clamping means sustained thereby, a grinding-wheel, said carriage having a swinging movement to carry the shear-clamping means toward and from the grinding-wheel, devices for moving the clamp and carriage with relation to the grinding-wheel 45 that the grinding-wheel may act from one to the other end of the shear-blade, and oppositely-acting means selectively engaging said 50 devices to cause it to move the clamp and carriage in opposite directions.

3. In a machine of the character described, a grinding-stone, a carriage, a shear-clamp supported thereon, a screw for reciprocating said carriage and clamp to move the shear-blade across the edge of the grinding-stone and means for reciprocating said carriage, said means consisting of a main drive-shaft, a gear thereon, an intermediate gear or pinion 55 mounted on the aforesaid screw and a reversing-gear mounted in the framing of the machine and means for engaging the intermediate gear with driving-gear or the reversing-gear.

4. In a machine of the character described, 65 a grinding-stone, a carriage, an arm mounted on said carriage, a shear-clamp carried by said arm, a guide-rod, a screw and means for operating said screw to move the shear-blade across the face of the stone, said means consisting of a driving-gear, an intermediate pinion or gear mounted upon the screw, and a reversing-gear, said drive-gear and reversing-gear being continually in mesh, and means for selectively engaging the intermediate pinion with either the driving-gear or reversing-gear. 70 75

5. In a machine of the character described, a grinding-stone, a two-part carriage, an arm supported thereby, a clamp thereon, a screw 80 for operating said two-part carriage, a swinging yoke carrying said screw, a set of gearing for imparting direct and reverse rotary motion to said screw, said set of gearing consisting of a driving-gear, a reversing-gear and an 85 intermediate gear, said intermediate gear being mounted on the screw.

6. In a machine of the character described, a grinding-stone, a two-part carriage, an arm mounted thereon, a clamp supported thereby, a screw for operating the carriage, a set 90 of gearing for imparting rotary motion in either direction to said screw, said set of gearing comprising a drive-gear, a reversing-gear, and an intermediate gear and spring-controlled means for throwing said intermediate gear into or out of mesh with either of the 95 other gears.

7. In a machine of the character described, a grinding-stone, a two-part carriage, an arm mounted thereon, a clamp supported thereby, a screw for operating the carriage, a swinging yoke carrying said screw, a set of 100 gearing for imparting rotary motion in either direction to said screw, said set of gearing comprising a drive-gear, a reversing-gear, 105 and an intermediate gear, said intermediate gear being mounted on the said screw, said swinging yoke being mounted to turn about a center between the axis of rotation of the drive-gear and the axis of rotation of the reversing-gear, whereby in rocking the said yoke in one or the other directions, the intermediate gear will be brought into mesh with 110 one or the other of the aforementioned gears. 115

8. In a machine of the character described, a grinding-stone, a guide-rod, a two-part carriage mounted to slide on said guide-rod and means for reciprocating said two-part carriage, the two parts of said carriage being pivoted together in a sliding relation to each other. 120

9. In a machine of the character described, a grinding-stone, a guide-rod, a two-part carriage mounted to slide on said guide-rod and means for reciprocating said two-part carriage, the two parts of said carriage being pivoted together in a sliding relation to each 125 other.

other, and a spring connected to said pivoted parts to counterbalance the weight of the shears or other article being ground.

10. In a machine of the class described, a grinding-wheel, a two-part carriage, a shear-clamp mounted thereon, a guide-rod for one end of said carriage, a screw-shaft engaging the other end of said carriage and provided with a pinion, a swinging frame carrying said screw-shaft, an oppositely-moving toothed wheel with either of which said pinion may be engaged to rotate said screw in one or the other direction.
11. In a machine of the class described, a

two-part carriage, means to guide the same, ¹⁵ means to slide the same, an arm engaging said carriage and provided with a shear-clamp and an adjustable spring to more or less counterbalance the weight of the shears held in the clamp. ²⁰

In testimony whereof I have signed my name to this specification in the presence of two subscribing witnesses.

EDWARD F. DAVIS.
